GOLF TEE

Benton G. Sickmiller, Mansfield, Ohio

Application July 6, 1936, Serial No. 89,059

2 Claims. (Cl. 273—33)

This invention relates, as indicated, to golf tees and more particularly to a type of golf tee which is designed to be permanent as well as adjustable, enabling it to meet the requirements 5 of every type of golfer.

The principal object of my invention is to provide a golf tee which will be permanent in its nature, thus disposing of the necessity of a golfer to carry with him more than one tee at any 10 time.

Another object of my invention is to provide a golf tee which is manufactured of a material that is durable.

Still another, and very important object of 15 this invention is to provide a permanent golf tee which can be adjusted as to height.

Other objects of my invention will appear as the description proceeds.

To the accomplishment of the foregoing and 20 related ends, said invention, then, consists of the elements hereinafter fully described and particularly pointed out in the claims.

The annexed drawing and following description set forth in detail certain structure embodying the invention, such disclosed elements constituting, however, but one of various structural forms in which the principle of the invention may be used.

In said annexed drawing:

30 Fig. 1 represents a perspective view of my adjustable golf tee.

Fig. 2 is a top view of the tee with all elements assembled.

Fig. 3 is a bottom view of the base and protuberance showing the neck which prevents the removal of the teeing element.

Fig. 4 is a sectional view of the base and protuberance only, taken substantially on the line indicated by the numerals 4—4 of Fig. 2.

40 Fig. 5 is a sectional view of the teeing element with the concavity in its upper portion.

Fig. 6 is a sectional view of the metallic element which prevents the removal of the teeing element.

45 Fig. 7 is a sectional view of the tee completely assembled showing the teeing element in the raised position.

It is a well known fact among those who play golf that the ordinary wooden peg or tee which 50 is in common use today are often broken or lost. Another well recognized disadvantage with the tee in common use today is the fact that occasionally the ground into which the tee must be placed will be too hard rendering it impossible 55 to place the tee properly.

As will be seen in the following description all objections to the ordinary tee are disposed of due to the fact that it is unnecessary to place my improved tee in the ground. It is also large enough to make it practically impossible to lose. Furthermore it is constructed of a material such that if it be struck by the club head in its downward motion said club head will be injured in no way.

Among those who play golf it will be found 10 that a great number find it necessary to tee their balls at various heights. I have anticipated this necessity and have taken care of it by constructing a tee which is capable of adjustment as to its height to meet all possible requirements as 15 will be more fully perceived as the description proceeds.

I have found that the best material to be used for my purpose is rubber. However, it is possible to manufacture this article out of pressed paper 20 or any other rather soft substance capable of withstanding a severe beating to which many golf tees are subjected. Since my improved tee consists only of three elements two of which are rubber and may be molded into the desired 25 shape its cost of manufacture will be extremely low thus enabling every person to own one. Obviously it is advisable to manufacture my tee in various colors such as is done at the present time to enable it to be easily seen on the fairway 30 or in tall grass.

I have found that when the club head strikes the tee in its downward path the tee may be knocked several yards in front of the player. This is obviously a disadvantage which must be 35 coped with if a lake or other body of water is situated in front of the tee. To overcome this objection I have provided the base of my tee with a small eyelet through which a string may be passed and the other end of which may either be 40 placed under the foot of the player or attached to a pin and placed in the ground in order to prevent the tee from leaving the ground in case it is hit by the club head.

Referring more particularly to the drawing 45 and more especially to Fig. 1 the base of the tee is indicated by the numeral 1. Arising vertically from said base and either attached thereto or integral therewith is a protuberance 2. This protuberance 2 is constructed in the form of a 50 tube which has in it a small indenture or neck the object of which will be later described.

Referring now more particularly to Figs. 5-6 the separate element 3 is made with a concavity 4 in its top and for the purpose of setting a ball 55

- thereon. This teeing element is also constructed with a slot or elongated hole 5 therein for the purpose of allowing the insertion of the metallic element 6.
- 5 It is necessary that it be made extremely difficult to remove the element 6 from the teeing element 3 and to the accomplishment of this end small fingers or prongs 7 are provided on two or more sides of the element 6. It will be seen that 10 no difficulty is encountered in placing the metallic element in the teeing element due to the downward direction of the prongs 7. However, since it is necessary when removing said element 6 to force the material of the teeing element in 15 a direction opposite to that of the prongs it will be extremely difficult to remove said element 6.

The smaller opening in the protuberance 2 is constructed of such size as to allow teeing element 3 to fit and slide snugly therein. It will 20 be obvious that various heights desired may be obtained by moving this element up or down within said protuberance 2. However, some precaution must be taken to prevent any inadvertent removal of the teeing element and for 25 this reason the element 6 has been provided. It will be noted that the base 8 of said element is constructed of such size so as to enable it to fit and slide snugly within the larger aperture extending from the base up through the protuberance. It will be noted that this element is able 30 to rise only to the point of indenture within the protuberance thus preventing its removal in an upward direction.

In assembling my improved golf tee the teeing 35 element 3 is first inserted in the aperture in the top of the protuberance 2 and pressed down until it is flush with said protuberance as more clearly shown in Fig. 1. The metallic element 6 is then inserted in the passageway 5 and the tee is then 40 ready for use. If a player desires his ball teed at a greater height, the teeing element 3 may be extended upwardly until the base portion 8 reaches the aforementioned indenture in the pro-

tuberance 2. It will be obvious that this tee may be constructed of different sizes as well as in different proportions in order to meet any necessary requirements.

The aperture which I have placed in the base 5 of my tee for the purpose of attaching a string or other securing means thereto is denoted by the numeral 9. This attachment of course is placed there merely as a guard such guard being made in any form desired. In Fig. 2 a string 10 10 is shown attached to a pin 11 which may be placed in the ground at any distance away from the player to hold the tee in place after being hit. However, a pin similar to that denoted by numeral 11 may be placed directly through the 15 hole 9 as in Fig. 3.

Other forms may be employed embodying the features of my invention instead of the one here explained, change being made as regards the form of construction, provided the elements 20 stated by any of the following claims or the equivalent of such stated claims be employed.

I therefore particularly point out and distinctly claim as my invention:

1. An adjustable golf tee comprising in combination a base having a tubular protuberance integral therewith and extending vertically upwardly therefrom, an element having a concavity in its top and slidably mounted in said base, and another element secured within said 30 slidably mounted element having a flared base thereon to prevent the removal of said slidably mounted element.

2. An adjustable golf tee comprising in combination a rubber base and tubular protuberance thereon, a rubber element having a concavity in its top and slidably mounted in said base, and a metallic element secured within said rubber element by means of prongs and having a flared base to prevent the removal of said 40 rubber element.

BENTON G. SICKMILLER.
